UNITED STATES PATENT OFFICE.

FRANK B. LEONARD, OF DETROIT, MICHIGAN.

HYDROCARBON-BURNER.

1,091,676.

Specification of Letters Patent. Patented Mar. 31, 1914.

Application filed October 7, 1912. Serial No. 724,249.

To all whom it may concern:

Be it known that I, FRANK B. LEONARD, citizen of the United States, residing at Detroit, county of Wayne, State of Michigan, have invented a certain new and useful Improvement in Hydrocarbon-Burners, and declare the following to be a full, clear, and exact description of the same, such as will enable others skilled in the art to which it pertains to make and use the same, reference being had to the accompanying drawings, which form a part of this specification.

My invention relates to an improvement in hydrocarbon burners, shown in the accompanying drawings and more particularly pointed out in the following specification and claims.

The object of my invention is to provide a device adapted especially for use in cooking stoves or ranges, though it may be employed equally well in connection with heating stoves or furnaces.

One of the features of the invention is to provide means for deflecting the flame from the burner toward the "water front" employed in a range to heat the water in a kitchen or range boiler, or toward the wall of the oven, when using the same in baking.

Another feature of the invention consists in so constructing the retort or vaporizer and burner that the burner may be readily disconnected from the retort or vaporizer to be replaced by one of larger or smaller capacity as may be required.

Another feature of the invention consists in providing a plate inserted in lieu of the ordinary grate, having openings for the passage of air to the burner and means for supporting the latter.

Another feature is the means employed to initially heat the burner to generate gas.

Other advantages and improvements will hereafter appear.

In the drawings accompanying this specification:—Figure 1 is an end elevation of a range with parts broken away and in section showing the burner in position in the fire-box. Fig. 2 is a side elevation of a range with the burner in cross-section and showing in dotted lines the deflector adjusted to project the flame toward the water front or oven. Fig. 3 is a perspective view of the burner and the plate employed in lieu of the usual grate. Fig. 4 is a perspective view of the generating device.

Referring now to the letters of reference

placed upon the drawings:—A denotes a range; B its fire-box; C a hot water front connected with the usual range boiler (not shown); and D the oven.

E is a burner consisting of a section of pipe perforated at e for the passage of gas and provided at one end with a closure cap E'.

F is a retort or vaporizer located directly above the burner, consisting of a pipe having at one end a goose-neck f connected to the burner E by means of a coupling G. The vaporizer F is illustrated as a straight pipe overlying the burner but it is obvious that the vaporizer may be coiled or of any suitable shape.

H is a fuel supply pipe leading from the tank H' and connected by suitable fittings with the vaporizer F.

I is a valve controlling the passage of oil through the pipe.

J, J', indicate disk-shaped deflectors suspended by collars j loosely sleeved on the vaporizer F—the collars being provided with a lug j' to engage a rocker arm K, the forward end of which projects through the wall of the stove and is provided with an operating handle K'.

k is a collar sleeved on the rocker arm adjacent to the outer wall of the stove to secure the arm against lateral displacement;—a similar collar sleeved on the arm may be located next to the inner face of the stove wall.

L is a plate of sheet metal supported at the bottom of the fire-box in lieu of the grate bars, having openings L' for the passage of air.

l are flanges integral with the plate forming an upstanding wall surrounding the openings,—the end walls being recessed to receive and support the burner E.

M is a device for initially heating the burner and consists of a wire frame m provided with a projecting rod m' serving as a handle.

N is a wick supported in the wire frame.

Having indicated the several parts by reference letters, the construction and operation of the burner will be readily understood. The valve I is first operated to deliver a small volume of oil from the supply tank to the burner E, the valve is then closed, and the wick N of the generating device 110 previously saturated in oil, is lighted, and placed under the burner as indicated in

dotted lines in Fig. 1. Upon the burner being heated sufficiently to convert the oil contained therein to gas, the latter is ignited and the valve opened that a further supply of oil may be delivered which is also generated into gas as it passes through the retort or vaporizer F over the flame of the burner. When it is desired to heat the water front connected with the range boiler, or the oven for baking purposes,—more quickly than it would be heated if the flame were not so deflected,—the rocker arm K is manually operated through the handle K', which being operably connected with both of the deflectors J, J, the latter are simultaneously adjusted so as to project the flame of the burners either toward the water front, or toward the oven as may be desired.

Having thus described my invention, what I claim is:

1. In a device of the character described, a burner tube having discharge ports, a vaporizer located directly above but spaced from the burner tube and having communication with the latter, a source of fuel supply communicating with the vaporizer, deflectors located above the discharge ports of the burner tube, and an operating shaft having connection with the deflectors for simultaneously swinging the same whereby the flame from the burner tube may be projected in different directions as required.
2. In a device of the character described, a burner tube having discharge ports, a vaporizer located directly above the burner tube and having communication with the latter, a source of fuel supply having communication with the vaporizer and through the communication between the burner tube and vaporizer with the burner tube, deflectors located above the discharge ports of the burner tube, means for simultaneously swinging said deflectors whereby the flame

from the burner tube may be projected in different directions as required, and an operating handle for the deflector swinging means.

3. In a device of the character described, a burner tube consisting of a section of pipe closed at one end and perforated for the passage of gas, a vaporizer located directly above and spaced from the burner tube and communicating therewith, a source of fuel supply for the vaporizer, a valve for controlling the delivery of fuel to the vaporizer, swinging disk deflectors suspended from the vaporizer above the gas discharge ports, and a manually operated rocker arm connected with the deflectors for adjusting the latter in either direction as required.

4. In a device of the character described, a burner tube, a vaporizer overlying the burner tube, a source of fuel supply for the vaporizer and burner tube, deflectors swingingly mounted on the vaporizer, and means for imparting a swinging movement to the deflectors, said swinging means including a rock shaft operatively connected with each deflector.

5. In a hydrocarbon burner having discharge ports for the passage of gas, an inclosure for said burner, swingingly mounted deflectors disposed above the discharge ports, an oscillating shaft connected to the deflectors for swinging the same, said shaft being journaled in one of the walls of the inclosure with one end of the shaft projecting without the inclosure for manual operation.

In testimony whereof, I sign this specification in the presence of two witnesses.

FRANK B. LEONARD.
